UNITED STATES PATENT OFFICE.

JOHN L. KAZMOUSKY, OF BOSTON, MASSACHUSETTS.

SYRINGE.

Application filed May 19, 1922. Serial No. 562,129.

To all whom it may concern:

Be it known that I, JOHN L. KAZMOUSKY, a citizen of the United States of America, and a resident of Boston, in the county of 5 Suffolk and Commonwealth of Massachusetts, and whose post-office address is #409 Broadway, South Boston, have invented certain new and useful Improvements in Syringes, of which the following is a specification.

This invention relates to syringes such for instance as are commonly used by dentists, physicians, and surgeons to inject anaesthetic fluids into the body of persons about 15 to undergo dental or surgical operations.

An object of the invention is to produce a syringe of this class that provides for the reinforcement of the fluid containing cylinder against internal pressure due to the 20 power applied to the fluid to force it therefrom.

A further object of the invention is to so construct and arrange the reinforcing devices as to compensate for rapid expansion 25 of the fluid cylinder, which is usually made of glass, in such manner that the possibilities of cylinder breakage due to expansion will be reduced to the minimum.

A still further object of the invention is 30 to provide a removable cylinder head, which has an outlet therein for the passage of fluid and to which the needle is attached, of such construction and arrangement that gradual or even sudden expansion of the said cylinder may take place without causing cylinder breakage.

Heretofore considerable trouble and inconvenience has been experienced due to 40 cylinder breakage caused by excess power being applied to the plunger to force the fluid through the small hole of the needle.

The hole of the needle is small compared 45 with the diameter of the plunger, and consequently when excess of power is applied to said plunger to force the fluid through said hole, the relief of the pressure is very gradual and unless the glass cylinder is unusually tough and without flaws and the ends thereof find perfect bearings in the 50 enclosing case, a crack is very apt to occur therein and quite often total destruction takes place at a critical time.

In a great majority of instances where 55 internal pressure caused the cylinders to crack, it has been found that the crack appeared lengthwise thereof, which indicated

the necessity of reinforcing or pressure resisting agents or mediums of a character that would immediately operate to relieve the cylinder of the brunt of the pressure 60 and at the same time capable of permitting the cylinder to expand during the sterilizing process without fear of cracking or breaking at those times.

The present invention includes in its scope 65 a means to reinforce the cylinder against destructive internal pressure, said means being preferably permanently attached to said cylinder, but not necessarily so, and of such a character as to compensate for the expansion of said cylinder during the sterilizing process to a degree sufficiently to allow the said process to be undertaken successfully and without detriment to the cylinder.

Heretofore it has been compulsory to remove the cylinder head, to which the needle is secured, and which snugly fits into the cylinder, before the sterilizing process took place.

The necessity of the removal of the head 80 was due to the unequal expansion of the head and the cylinder when they were not separated but were plunged into boiling liquid and allowed to remain there for indefinite periods.

The unequal expansion almost invariably caused the cylinder to crack if not actually break, the occurrence of either being sufficient to render it valueless for further use.

The present invention also includes a 90 cylinder head of such construction and arrangement as to efficiently function in its intended capacity, and furthermore the necessity of its removal prior to the sterilizing operation is eliminated, as it is of such 95 character as to adapt itself to heat conditions in such a satisfactory manner that its presence in the cylinder, during the said operations, causes no ill effects thereupon.

It is not known that syringes of this class 100 have ever been supplied with means to relieve the cylinders thereof of destructive internal pressure, which means is also capable of undergoing the sterilizing process while attached to the cylinder without detriment 105 thereto.

Nor is it known that a cylinder head has ever been used that may be assembled with the fragile cylinder and in that condition subjected to immersion in boiling water or 110 other sterilizing means for comparatively long intervals without detriment to the said

cylinder, consequently it is not the intention to limit this invention to the precise construction and arrangement herein shown as it is obvious that changes might be made 5 therein without departing from its spirit and scope.

The invention further consists in certain novel features of construction and arrangement which will be fully understood from a 10 description of the drawings and the claims hereinafter given.

Of the drawings:

Figure 1 represents in side elevation one form of syringe to which the present invention 15 is applied.

Figure 2 is a view similar to Figure 1 but showing the casing in section and the cylinder partially broken away to show the piston or plunger therein.

20 Figure 3 an enlarged section view through the cylinder as removed from the casing, showing the preferred form of reinforcing agents permanently attached thereto and the cylinder head in elevation.

25 Figure 4 a section on the line 4—4 Figure 3.

Figure 5 an enlarged view similar to the upper portion of Figure 3 showing a slightly modified form of attaching one of the reinforcing agents to the cylinder.

30 Figure 6 a bottom plan view of the casing showing squared hole to be described.

Like characters represent like parts throughout the several figures of the drawings.

Referring to the drawings:

The drawings herewith show a form of syringe conveniently adapted to illustrate the application of the present invention, 40 but it will be obvious that it may be applied to other forms of syringes with equally efficient results.

The casing 10 is or may be of any usual size or form desired, and may have openings 45 therein as at 11 through which a view of the cylinder 12 may be had to note the contents thereof.

Suitable finger grips 13 may be provided which are adapted to act in conjunction 50 with the bar 14 against which the base of the thumb will be pressed when it is desired to forcibly eject fluid from the said cylinder. The said bar 14 is located as usual at the end of the piston or plunger rod 15 to 55 which is attached in any suitable manner the plunger or piston head 16 as usual.

In this instance the casing 10 has a square sided opening at the bottom thereof through which a portion of the plug-like member or cylinder head 17 protrudes, the said head being slabbed or square sided as at 18 to engage the square sided opening referred to, and also has a shoulder 19 formed thereon which meets and finds a stop against the bottom 20 of said casing between which

and a screw plug 22 the cylinder 12 is clamped in place. At the top the said casing is provided with an internally threaded opening 21 into which is screwed the piston rod guide plug 22.

70 By unscrewing the said plug 22 the cylinder 12 and the head 17 with the attached needle 23 may be withdrawn from the casing 10.

The syringe just briefly described is a 75 structure that is very familiar to the medical profession.

The present invention, while very simpl' 80 in itself, has proved to be a very efficient one and is particularly valuable when an anesthetic has been used and the syringe allowed to stand a while before being taken apart to sterilize.

Certain anaesthetics have a tendency to 85 cause the cylinder head to "freeze" in the cylinder if not cleaned directly after using, and in such cases an attempt to separate them results in breakage of the cylinder, and in the past when the cylinder and the head when assembled were subjected to the sterilizing action of boiling water, the cylinder generally cracked or became broken.

In the present instance each end of the cylinder 12 is provided with a reinforcing 90 ring or ferrule 25 and if desired an additional one may be located as at 26.

The said ferrules are mounted on the cylinder in a novel manner; grooves 27 being 100 cut in the cylinder and similar grooves 28 being cut in the ferrules, the said ferrules which are slightly larger in diameter than the cylinder are positioned on the cylinder and a soft metal 29 is run between them to fill the space therebetween.

The said metal also fills in the grooves 27 and 28 in such manner that when the metal becomes cool and hardens the ferrule will be securely held from longitudinal movement relatively to the cylinder.

If preferred the ferrule may be made as 110 shown in Figure 5 wherein the ends of the ferrule are turned inwardly to form a wide groove and the metal run in to fill the space as before, thus effectively securing the ferrule against longitudinal movement.

In either instance, the metal 29 is one that 115 preferably approximates the expansibility of glass and softer than the metal of the ferrule and consequently affords a cushion-like band around the cylinder between it and the ferrule that receives the brunt of cylinder pressure and transmits it to the ferrule and yet capable of yielding slightly when called upon to do so.

120 It will be evident that ferrules mounted and disposed as above described will greatly add to the pressure resisting qualities of the fragile cylinder, and furthermore they need not be removed therefrom when it is 125 to be sterilized.

Another feature of the invention consists in the novel construction of the cylinder head or plug 17 which is composed chiefly of metal usually used in such devices and is 5 centrally bored at 30 to form a passage for the fluid from the cylinder to the passage 31 of the needle 23. A deep countersink 32 is made at the upper end of the plug 17 of such diameter as to leave a thin shell 33 into 10 which is run a quantity of soft metal 34 having the same qualities and function as the metal 29, through which a hole 35 is bored to communicate with hole 30 of the plug 17.

Necessarily the plug 17 must fit snugly in 15 the cylinder 12 in a non-leakable manner, and therefore if no provision were made to compensate for the unequal expansion of the metal plug and the glass cylinder or if no provision were made for one or the other 20 to yield it will be readily seen that the cylinder would either crack or break if immersed in boiling water when assembled.

The use of the metal 34, however, in conjunction with the thin shell 33 forms a structure 25 which meets the requirements and consequently if the plug cannot be readily separated from the cylinder they may be put into boiling water and allowed to remain there the required time without causing injury to 30 the said cylinder.

It will be noted that a portion of the plug 17 is slightly conical as at 40 which does not contact with the cylinder because of the fact that at approximately that part the shell 33 35 joins the main body of the plug and the resiliency thereof is greatly limited and if contact took place the efficiency of the cushion-like metal would be lost.

The wall or shell 33 is so thin that it cannot 40 exert sufficient outward pressure on the cylinder to cause it any injury when expansion takes place, and will quickly yield to pressure due to contacting of the cylinder.

The soft metal plug 34 serves to yieldingly 45 reinforce the shell 33 so that the shell will not become misshapen as would be the case if it was not used. Furthermore it is desirable to eject all, or nearly all the liquid in the cylinder, and if a plug such as 34 was 50 not used, an amount of liquid equal to the capacity of the countersunk portion 32 would be left therein as the piston head 16 cannot advance beyond or into the said shell 33.

55 It will be understood that the shell 33 must yield to the expanding and contracting actions of the heavier parts 12 and 34, the latter having approximately the same expansibility as the cylinder 12, thus a sufficiently tight joint is made between the cylinder 12 and head 17 without fear of breakage to the cylinder, and more of the liquid 60 may be ejected from the cylinder than if the soft metal plug 34 was not used.

65 Having described the invention I claim:

1. In a syringe of the class described, a cylinder; a cylinder plug having an outlet therein smaller in diameter than the bore of said cylinder; a piston adapted to force fluid from said cylinder through said outlet; and means comprising a plurality of soft metal bands having hard metal bands superposed thereon so arranged as to form yielding reinforcements for said cylinder whereby excess pressure in said cylinder will be transmitted to said reinforcements, thereby enabling said cylinder to resist said pressure. 70 75

2. In a syringe of the class described, a cylinder; a cylinder plug having an outlet therein smaller in diameter than the bore of said cylinder; a plunger adapted to force fluid from said cylinder through said outlet; and cylinder reinforcing means comprising soft metal cylinder encircling bands having hard metal bands superposed thereon whereby excess pressure in said cylinder will be transmitted to said reinforcement, thereby enabling said cylinder to resist said pressure. 80 85

3. In a syringe of the class described, a cylinder; a cylinder head having an outlet therein smaller in diameter than the bore of said cylinder; a piston adapted to force fluid from said cylinder through said outlet; ferrules adjacent the ends of said cylinder composed of comparatively hard metal; cushions of comparatively soft metal intermediate said ferrules and said cylinder; and means formed on said cylinder and in said ferrules adapted to coact with said soft metal to retain said ferrules, cushions and cylinder in operative relation. 90 95 100

4. In a device of the class described, a cylinder; a plug in one end thereof having an outlet therethrough; a piston adapted to eject fluid from said cylinder through said outlet; a plurality of ferrules encircling said cylinder; cushions of soft metal interposed between said cylinder and said ferrules; and means coacting with said soft metal to retain 105 said ferrules relatively to said cylinder. 110

5. In a syringe of the class described, a cylinder; a plug in one end thereof having an outlet therethrough; a piston adapted to eject fluid from said cylinder through said outlet; a plurality of ferrules encircling said cylinder; cushions of soft metal interposed between said ferrules and said cylinder; said cylinder having depressions therein adapted to receive a quantity of said soft metal from the main body thereof; means coacting with said ferrules and said soft metal to retain said ferrules relatively to said cylinder; and a casing for said cylinder. 115 120

6. In a syringe of the class described, a cylinder; a plug in one end thereof having an outlet therethrough; a piston adapted to expel fluid from said cylinder through said outlet; a ferrule of comparatively hard metal at each end of said cylinder; said cylin- 125 130

der having grooves therein to receive soft metal; said ferrules having grooves therein also adapted to receive soft metal; a filling of relatively soft metal having approximately the same expansibility as glass interposed between said ferrules and said cylinder in such manner as to coat with said grooves whereby said ferrules are retained in position on said cylinder; and a casing 5 adapted to receive and retain said cylinder in operative position.

7. In a syringe of the class described, a cylinder; a piston adapted to force fluid from said cylinder through the outlet passage; reinforcing means coacting with said cylinder adapted to resist internal pressure therein; a plug at one end of said cylinder having an outlet passage therethrough, said plug comprising a hard metal body bored 15 at its inner end to provide a thin walled receptacle; and a reinforcing plug of soft metal in said receptacle.

8. In a syringe of the class described, a cylinder; a piston adapted to force fluid from said cylinder; a plug in said cylinder having an outlet therethrough, said plug being centrally bored and supplied with a fitting of relatively soft metal to thereby reinforce said bored shell.

30 9. In a syringe of the class described, a glass cylinder; a piston adapted to force fluid from said cylinder; a plug having a passage therethrough adapted to be inserted in one end of said cylinder, the cylinder contacting portion of which is reinforced by a metal softer in nature than that of the plug and a casing adapted to surround said cylinder.

10. In a device of the class described, a casing; a cylinder therein; and cylinder reinforcing means intermediate said casing and said cylinder, said means comprising a plurality of soft metallic bands having hard metallic bands superposed thereon. 40

11. In a device of the class described, a casing; a cylinder therein; means to secure said cylinder in said casing; said cylinder having soft metal bands adjacent its ends; said soft metal bands having hard metal bands superposed thereon and extending beyond said cylinder whereby contact of said cylinder with said casing and said securing means is prevented. 45

50 12. In a device of the class described, a casing; a cylinder therein; means to secure said cylinder in said casing; said cylinder having soft metal bands encircling it adjacent its ends; said soft metal bands having hard metal bands superposed thereon and adapted to overlie the outer ends of said soft metal bands whereby pressure due to said cylinder securing means will be transmitted to said soft metal bands thereby relieving said cylinder from longitudinal crushing pressure. 55

60 13. In a device of the class described, a casing; a cylinder therein; and cylinder reinforcing means intermediate said casing and said cylinder and comprising soft metallic bands mounted on said cylinder to thereby eliminate breakage thereof when subjected to extreme internal pressure. 70

Signed by me at Boston, Mass. this 16th day of May, 1922.

JOHN L. KAZMOUSKY.
